UNITED STATES PATENT OFFICE

GEORGE W. HEENE, OF CLEVELAND, OHIO

STAMPING MACHINE

Application filed February 13, 1929. Serial No. 339,688.

Certain types of stamping machines which are employed to engrave a ring or other emblem on a blank and which also usually mechanically vend the stamped blank to a purchaser, include a magazine unit. This magazine contains a supply of blanks which are fed to the machine to have the stamping operation performed thereon as the occasion demands. In the now known constructions of the machines, the magazine units are removable so that they may be refilled with blanks after they are empty. This property of detachability of the magazine unit, is an essential, but has caused some little trouble due to the fact that when a magazine unit after being filled is again put into operative position on the machine, it is not properly fastened into place by the person refilling the magazine. Under such conditions, or under conditions wherein the magazine is not properly held in position, damage to the machine very often takes place.

It is the primary aim of this invention to provide novel instrumentalities for holding the magazine unit of the stamping machine in proper operative position, and which instrumentalities provide for the quick and easy removal and replacement of the magazine to and from its operative position.

In attaining the end above noted, I provide the supporting frame of the machine with projections which are adapted to enter recesses in the base of the magazine unit, and a cam means which functions to either positively maintain the engagement of the lugs and recesses aforesaid by rigidly holding the base of the magazine against the supporting framework, or which may be operated to release the connection between the base and supporting frame as previously outlined.

A particular feature of the invention resides in the mounting of the cam means set out in the preceding paragraph in the framework of the machine. The supporting means for the cam is so arranged that the magazine may be easily moved into and out of positions wherein the lugs and recesses are in engagement with each other. Moreover, the cam is so mounted and provided with an operating member, that it is readily available to a per-

son who is desirous of removing or releasing the magazine unit.

With these and other objects and advantages in view as will in part become apparent and in part be hereinafter described, my invention contains certain combinations, constructions and arrangements of parts as will be hereinafter specified and claimed.

For a full and more complete understanding of the invention, reference may be had to the following description and accompanying drawings, in which—

Figure 1 is a view in elevation from the side, of that portion of the stamping machine with which this invention is particularly identified.

Figure 2 is a section taken about on the line 2—2 of Figure 1 which develops certain portions of the stamping machine in section and others in elevation.

Figure 3 is a perspective illustration of the lower portion of the magazine unit, bringing out particularly the base portion thereof.

Figure 4 is a plan view of the supporting framework for the magazine unit, with the latter part removed from the former.

Figure 5 is an enlarged detail perspective showing of the cam means which holds the magazine in place.

While a preferred specific embodiment of the invention is herein set forth, it is to be understood that I am not to be limited to the exact constructions illustrated and described, because various modifications of these details may be provided in putting the invention into practice within the purview of the appended claims.

Throughout the various figures of the drawings and following description, like reference characters denote corresponding parts.

First referring to Figures 1 and 2, the base of the machine is referred to generally by the reference character A. Mounted on the base A is the stamping mechanism which may be described briefly as comprising dies B, hammer C, hammer operating means D, ejector mechanism E, discharge chute F including guide F¹, and a magazine unit G with which are associated the connecting instrumentalities.

ties which are referred to generally by the reference character H.

The magazine unit G comprises the tubular member 1 and the base portion 2, these two parts being connected together in any preferred manner. The member 1 is provided with openings 3 which serve as sight means when one wants to determine how many metal blanks are contained in the magazine. Needless to say, the metal blanks which the magazine houses, are of disc-like formation and are superimposed one above the other in the housing. A U-shaped member 4 is adapted to be inserted in openings 5 which extend through the lower portion of the magazine G to prevent the blanks from falling out of the latter when the magazine is being positioned. After it is properly put in place in the machine, the member 4 may be removed so as to permit the blanks to feed into the ejector mechanism E.

The ejector mechanism E functions to remove a blank which has been suitably stamped by the dies B and hammer C, and discharge 25 the same into the discharge chute F. At the same time the ejector mechanism E functions to take a blank from the magazine 1 and place it in position with respect to the dies B and hammer C so that the latter may properly 30 operate thereon to stamp the desired insignia on the blank.

Side members 6 that serve as sort of guides for part of the ejector mechanism E, also constitute a supporting frame for the magazine unit G. Interlocking means between the base 2 and the members 6 is provided in the form of pins 7 and openings 8. In the present instance the pins 7 are shown as being located on a supporting framework while the 40 openings 8 are in the base 2. It is readily appreciable that this arrangement might well be reversed.

In order to place the magazine in position, the base 2 is placed on supporting frame 6 so that the pins 7 enter the holes 8. The camming instrumentalities which are now to be described, are then operated so that upward movement of the magazine base 2 is prevented and the latter is rigidly clamped against the supporting framework 6.

The camming instrumentalities comprise a bracket 9 which is rigidly fastened to suitable structure on the machine as by the screws shown at 10 and this bracket pivotally carries at its upper end a cam member 11, which cam member is provided with an operating member 12. It is obvious that when the operating member 12 is availed of to swing the member 11 so that its surface which is closest 55 to the pivotal mounting is disposed downwardly, there is a space provided between the cam member 11 and the base 2 and this space permits of the placing of the base member 2 in position or the removal thereof from the 60 machine. After the magazine unit G is posi-

tioned a turning of the cam member by its operating member 12 causes the cam surface of the member 11 to firmly clamp the base 2 against the supporting framework.

Having thus described my invention, what I claim as new and desire to secure by Letters Patent of the United States, is:—

1. In a stamping machine of the class described, the combination with a frame member and a magazine, of fastening devices for 75 securing the magazine to the frame member, said fastening devices comprising complementary lugs and recesses adapted to prevent movement in one plane, and means for holding the complementary lugs and recesses in engagement.

2. In a stamping machine of the class described, the combination with a frame member and a magazine, of instrumentalities for fastening the magazine to the frame member, 85 said instrumentalities comprising means for preventing movement in one direction, and a cam member for holding the last named means in operative position.

3. In a stamping machine of the class described, the combination with a frame member and a magazine, of mechanism for securing the magazine to the frame member, said mechanism including complementary lugs and recesses for preventing movement in one plane 95 and a cam member for holding said lugs and recesses in engagement.

4. In a stamping machine of the class described, the combination with a frame member, of a magazine having a base portion, recesses in said base portion, complementary lugs on the frame member adapted slidably to engage said recesses, and further means carried by the frame member for holding said lugs and recesses in engagement.

5. In a stamping machine of the class described, the combination with a frame member, of a magazine having a base member adapted to abut the frame member, means on the frame member and the base member of the magazine for preventing relative sliding action between said members and a cam carried by the frame member, said cam being rotatable to hold the magazine in abutment with the frame member.

6. In a stamping machine of the class described, the combination with a frame member, of a magazine, complementary lugs and recesses carried by the frame member and the magazine, and a pivoted cam member carried by the frame member, said cam member being rotatable to hold the complementary lugs and recesses in engagement.

In testimony whereof I affix my signature.
GEORGE W. HEENE.
